(57) CLAIM

The ornamental design for a laundry device, as shown and described.

DESCRIPTION

FIG. 1 is a top, front, and left side perspective view of a laundry device, showing my new design;

FIG. 2 is a left side elevation view thereof;

FIG. 3 is a front elevation view thereof;

FIG. 4 is a right side elevation view thereof;

FIG. 5 is a rear elevation view thereof;

FIG. 6 is a top plan view thereof; and,

FIG. 7 is a bottom plan view thereof.

Any portions shown in dashed lines are included for illustration purposes only and form no part of the claimed design.
